(57) **CLAIM**

The ornamental design for an electrical connector assembly, as shown and described.

DESCRIPTION

FIG. 1 is a front top right perspective view of an electrical connector assembly showing my new design;

FIG. 2 is a bottom left rear perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof;

FIG. 8 is a rear view thereof;

FIG. 9 is a front top right perspective view in use condition;

FIG. 10 is a bottom left rear perspective view thereof;

FIG. 11 is a top view thereof;

FIG. 12 is a bottom view thereof;

FIG. 13 is a right side view thereof;

FIG. 14 is a left side view thereof;

FIG. 15 is a front view thereof; and,

FIG. 16 is a rear view thereof.

In the figure drawings, the even-broken line is included for the purpose of illustrating environment and forms no part of the claimed design.
